(Cl. D26—1)

To all whom it may concern:

Be it known that we, Karl W. Youngbeck and Henry J. Glueckstein, citizens of the United States, residing at Milwaukee, in the county of Milwaukee and State of Wisconsin, have invented a new, original, and ornamental Design for a Miniature Twin Variable Resistor, of which the following is a specification, reference being had to the accompanying drawing, forming a part thereof, and in which:

Fig. 1 is a view in side elevation of a miniature twin variable resistor, showing our new design;

Fig. 2 is a view thereof in front elevation; and
Fig. 3 is a view thereof in rear elevation.

We claim:

The ornamental design for a miniature twin variable resistor, as shown.

KARL W. YOUNGBECK.
HENRY J. GLUECKSTEIN.
